UNITED STATES PATENT OFFICE.

WILLIAM F. IVY, OF ROCK ISLAND, ILLINOIS.

DESIGN FOR A FLAG.

55,275.

Specification for Design.

Patented May 25, 1920.

Application filed September 13, 1919. Serial No. 323,665. Term of patent 3½ years.

To all whom it may concern:

Be it known that I, WILLIAM F. IVY, a citizen of the United States, residing at Rock Island, in the county of Rock Island and State of Illinois, have invented a new, original, and ornamental Design for a Flag, of which the following is a specification, reference being had to the accompanying drawing, forming a part thereof.

The figure is a view of the flag showing my new design.

I claim:

The ornamental design for a flag as shown.

WILLIAM F. IVY.

Witnesses:

S. M. FITZ PATRICK,
ALICE B. IVY.
